Primary Examiner — Kevin Rudzinski(74) *Attorney, Agent, or Firm* — King & Spalding**CLAIM**

(57) The ornamental design for a recessed luminaire housing top, as shown and described.

DESCRIPTION

FIG. 1 is a top perspective view of a recessed luminaire housing top, showing our new design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front side elevation view thereof; and,

FIG. 8 is a rear side elevation view thereof.

The broken lines that illustrate portions of the recessed luminaire housing form no part of the claimed design.
